UNITED STATES PATENT OFFICE

2,660,637

CIRCUIT BREAKER

William A. Thomas, Plainville, Conn., assignor,
by mesne assignments, to General Electric
Company, a corporation of New York

Application November 18, 1949, Serial No. 128,096

6 Claims. (Cl. 200—88)

1

My invention relates to circuit breakers and more particularly to what are termed air circuit breakers of small size.

A prime object is to provide a circuit breaker of this type that is compact, simple in construction, flexible in action, highly efficient in operation and economical to manufacture.

Another object is to provide a circuit breaker in which the contacts are held closed in such a manner that they cannot be jarred open.

Another object is to provide a circuit breaker in which the contact pressure is much greater than the latch pressure.

Many circuit breakers are so constructed that when automatically tripped the manually actuated member must be given two distinct movements in order to reclose the circuit. It is one of my objects to provide a circuit breaker mechanism of this type which can be reclosed in the same manner after automatic tripping as after manual opening—that is, by one movement of the handle.

It is a more particular object of the invention to provide, in a floating lever type of manually operable current responsive tripped electric circuit breaker, new and improved means for automatically resetting the current responsive latching means after tripping so that no manual resetting movement is necessary following overcurrent trip, and to do so while providing also trip-free operation.

Another object is to ensure a sliding engagement of a movable contact against a stationary contact in closing a circuit and before breaking the circuit.

Fig. 1 is an inside view of a construction embodying my invention, the parts being shown in a closed circuit relation, and parts being shown in section.

Fig. 2 is a sectional view taken on the plane of the line 2—2 of Fig. 1.

Fig. 3 is a sectional view taken on the plane of the line 3—3 of Fig. 1.

Fig. 4 is a fragmentary sectional view on the plane of the line 4—4 of Fig. 1.

Fig. 5 is a fragmentary perspective view showing the thermostatic latch and magnetic release.

Fig. 6 is an inside view similar to Fig. 1 but showing the position of the parts in the position they occupy when automatically released.

The mechanism is enclosed between the two parts 1, 1' of an insulating housing suitably secured together for instance by screws or rivets 2, 3.

The angular conductor piece 9 has a circuit 55 a snap action.

2

terminal 10 at one end and a switch contact 11 at the other end. The other circuit terminal 12 is secured in place by the screw 13.

The switch member or floating arm 13 which coacts at one end with contact 11 has a pin and slot connection 14, 14' with the walls of the housing. This member 13 is biased toward the open circuit position by spring 15. A bimetal strip 16 is secured at its inner end to an arm 17 of the terminal member 12 with its low expansion side toward part 17. The screw 18 is adjustable through arm 19 of member 12 and engages arm 17 for calibrating the breaker.

The upper end of the bimetal strip is connected 15 by a flexible conductor 20 with the floating arm 13. The field piece of magnet 21 is secured to bimetal strip 16 and has an armature 22 pivoted at 23 between the housing walls. This armature has a lever arm 24 which extends at an 20 angle to the main armature member and is under pressure of spring 25 which biases the armature toward the right as viewed in Fig. 1. The action of the bimetal under heat or under the attraction of the magnet is to move the armature toward the left.

A floating rocker member 27 has a pivot pin 28 which can rotate and slide in a slot 28' in the housing. This rocker has a cam-like shoulder 29 which coacts with a cam 30 on the switch arm 13.

The actuating lever 31 is pivoted at 32 in the housing and has an arm 33 with a cam surface 34 which coacts with a cam portion 35 of rocker 27.

In the closed circuit position, the cam part 34 of the lever 31 tightly holds the rocker 27 in the 35 position of Fig. 1 where the tip of the rocker engages a shoulder 36 on the armature 22 and the cam 29 presses on the cam 30 of the floating switch member 13 and holds the spring 15 under compression and positively holds the switch member in the closed circuit position where it cannot jar loose.

It will be noted that the spring 15 presses the switch member 13 upwardly so that the cam 30 presses against the cam 29 on the rocker 27 thus pressing the cam 35 on the rocker 27 against the cam 34 on the member 33.

When the lever 31 is manually turned toward the left from the position of Fig. 1 the cam 34 moves to the right. When cam 34 passes to the right of cam 35, the rocker 27 is free to rise in slot 28'. The rocker thus tilts counter-clockwise so that cam 29 slips over cam 30 on switch member 13 and thus permits the spring 15 to tilt the switch member 13 and open the circuit with

In case of a heavy surge of current or in case of a gradual load above that rated for the circuit breaker, the armature 22 will be drawn away from rocker member 27 so that the rocker will tilt counter-clockwise thus disengaging cam 29 from cam 33 and releasing member 13 so that spring 15 can suddenly throw the parts to the position of Fig. 6 and break the circuit. In tilting counter-clockwise after latch release the rocker lever 27 engages a projection 33a on the right end of the camming arm 33 and rotates the operating lever 31 and the cam 33 in a counter-clockwise direction to its circuit opening position. With the operating lever 31 and the cam 33 in the circuit opening position, the rocker lever 27, being still pressed upward by the spring 15, tilts clockwise about the cam surface 34 until the pin 28 comes near the top of the slot 28'. This movement resets the rocker lever 27 against a positioning surface of the cam 33 as shown at Fig. 6. From this position, the breaker can be reclosed as soon as the latch shoulder 36 is reset by simply pressing the lever 31 from the "off" position of Fig. 6 to the "on" position of Fig. 1. It will thus be seen that in this construction there is an "on" position and an "off" position but no reset position of the manual lever, such as is common in many circuit breakers.

In case the rocker 27 is automatically released the main spring 15 will move the switch arm 13 and open the circuit even if the actuating lever is manually held in the "on" position. In this case the rocker lever 27 tilts counter-clockwise after latch release under the action of the spring 15, pressing against the cam 34 and engaging the tip 33a of the cam arm 33. If the lever is then released, it will fly to the "off" position because of the pressure applied to its end 33a by the rocker lever 27, and the rocker lever 27 will then tilt clockwise as before about the cam projection 34 until the pin 28 is near the top of the slot 28'. The mechanism is then ready to reclose the circuit manually, being in the position of Fig. 6.

This arrangement ensures a trip free action in which the circuit is broken at a maximum speed when the breaker is released either manually or automatically. In either case the cam shoulder 29 is first released for movement upward and to the right. The spring 15, pressing the switch member 13 upward against the shoulder 29, first raises the pivot pin 14 of the switch lever 13 to the top of the slot 14'. This upward sliding movement of the pin 14 causes the movable contact tip to slide along the surface of the stationary contact 11, thus preventing any tendency to stick. The cam shoulder 29 then slides over the cam shoulder 38 and permits the spring 15 to raise the right end of the lever 13 to the open circuit position of Fig. 6. The spring has its maximum power at the very start of the opening movement so as to start the separation of the contacts at high speed. This results in superior interruption in a small circuit breaker of this type. In fact such a switch has proved to be several times as fast as commercially comparable breakers. It is possible with this type of breaker to obtain contact pressure up to seven or eight times the latch pressure whereas in other small breakers the ratio is as low as one or two to one.

The gases resulting from the arc formed in the chamber 40 when breaking the circuit are allowed to escape through the tortuous passages 41 formed in the housing 7. This labyrinth is further divided into several compartments by the perfo-

rated fibre baffles 42 and 43 which act to gradually cool and lower the pressure of the gases resulting from the arc. This arrangement ensures a safer breaker free from the usual dangers from fire or flame from the exhaust port.

6 I claim:

1. In a circuit breaker, a base, a stationary contact mounted on said base, a rigid movable switch arm having a pin and slot connection with said base at one end and having a movable contact at the other end cooperable with said stationary contact, said pin and slot connection providing transverse sliding and pivotal movement of said arm, a spring engaging said switch arm intermediate said movable contact and said one end and biasing said switch arm to an open circuit position, and manually operable camming means engaging said switch arm intermediate said contact and said spring to force said arm to a circuit closing position and lock it against the biasing action of said spring, said spring upon release of said manually operable means first sliding said one end of said switch arm transversely thereby to slide said contacts one upon the other and then separating said contacts by rotation of said switch arm about said one end.

2. In a circuit breaker, a stationary contact, a rigid movable switch arm having at one end a movable contact cooperating with said fixed contact, means mounting said switch arm at its other end for pivotal sliding movement in a direction transverse of said switch arm, a spring engaging said arm intermediate its ends and biasing said arm to an open circuit position, said switch arm having an inclined camming surface intermediate said spring and said one end, and manually operable actuating means including a pivotally mounting camming projection engaging said inclined surface and shaped to permit abrupt circuit opening movement of said switch arm, said switch arm when released by said camming projection first sliding transversely on said pivotal mounting to slide said contacts one upon the other and then turning on said pivotal mounting to separate said contacts.

3. In a circuit breaker, a base, a switch member movably mounted on said base, cooperating switch contacts controlled by said switch member, means biasing said switch member to a circuit opening position, a rocker lever mounted on said base intermediate its ends on a sliding pivot for movement into engagement with said switch member, current responsive means releasably securing one end of said rocker lever against movement, an actuating cam mounted on said base on a fixed pivot and having an actuating projection engaging said rocker lever to tilt said lever about said one end thereby to move said switch member between circuit opening and circuit closing positions, said rocker lever when released with said actuating cam in its circuit closing position tilting about said sliding pivot to release said switch member and engaging said cam to move said cam to its circuit opening position, and positioning means on said cam engaging said rocker lever when said cam is in its circuit opening position to position said rocker lever for automatic resetting of said current responsive means.

4. In a circuit breaker, a base, a switch member movably mounted on said base, cooperating switch contacts controlled by said switch member, means biasing said switch member to a circuit opening position, a rocker lever mounted on said base intermediate its ends on a transversely slid able pivot, current responsive means re-

leasably securing one end of said rocker lever against movement, a manually operable actuating cam rotatably mounted on said base and having a projection engaging said rocker lever intermediate said one end and said slideable pivot to slide said pivot, said rocker arm when so moved engaging said switch arm to close and open said contacts and when released by said current responsive means rotating on said slideable pivot to release said switch member for contact opening movement, means engaging the other end of said rocker arm when released by said current responsive means to rotate said actuating cam to its circuit opening position, and a positioning surface on said actuating cam engaging said rocker arm in said circuit opening position of said actuating cam to position said rocker arm for automatic resetting of said current responsive means, whereby normal manual circuit closing movement of said actuating cam after current responsive opening of said contacts recloses said contacts.

5. In a circuit breaker, a base, a rigid movable switch arm mounted on said base for pivotal movement about one end, circuit controlling means actuated by the other end of said switch arm, a spring fixedly mounted on said base at one end and engaging said switch arm to bias said arm to a circuit opening position, a rocker lever mounted on said base intermediate its ends on a sliding pivot for movement transversely of the length of said switch arm, said rocker lever having a camming projection engaging said switch arm intermediate said spring and said other end of said switch arm, current responsive means releasably securing one end of said rocker lever against movement, and an operating lever pivotally mounted on said base and including an actuating cam engaging said rocker lever intermediate said one end and said sliding pivot, said operating lever including a portion positioned to be engaged by said rocker lever when released to turn said operating lever to its off position and said actuating cam having a portion engaging said rocker lever when said operating lever is in said off position to position said rocker lever for automatic resetting of said current responsive means.

6. In a circuit breaker, a base, a stationary contact mounted on said base, a rigid switch arm, means mounting said switch arm on said base for transverse sliding and pivotal movement at one end, a movable contact carried by the other end of said switch arm for cooperation with said stationary contact, a spring fixedly mounted on said

base at one end and engaging said switch arm at a point intermediate its ends to bias said switch arm to a circuit opening position, a rocker lever disposed in substantially parallel spaced relation with said switch arm and having a camming projection engaging said switch arm intermediate said spring and said movable contact, means mounting said rocker lever on said base for transverse sliding and pivotal movement at a point intermediate its ends, current responsive means releasably securing one end of said rocker lever against movement, and manually operable means including a rotatable actuating cam pivotally mounted on said base and having an actuating projection engaging said rocker lever intermediate said one end and its pivotal mounting, said actuating projection normally tilting said rocker lever about its said one end thereby to press said camming projection against said switch arm and move said switch arm to circuit closing position when said actuating cam is moved to a circuit closing position and said rocker lever when released by said current responsive means rotating about its intermediate pivotal mounting to release said switch arm for circuit opening movement, a second projection on said actuating cam disposed for engagement with the other end of said rocker lever when released by said current responsive means to rotate said actuating cam to a circuit opening position, and a positioning surface on said actuating cam to engage said rocker lever and position it for automatic reset of said current responsive means when said actuating cam is in said circuit opening position.

35 WILLIAM A. THOMAS.
